PORTABLE POWER SHEAR FOR SHEET MATERIAL

Melford H. Docken, Minneapolis, Minn., assignor to
W.P.B. Industrial Products, Inc., Skokie, Ill., a corpo-
ration of Illinois

Filed Sept. 23, 1958, Ser. No. 52,738

Term of patent 14 years

(Cl. D54—14)

FIG. 1

FIG. 2

FIG. 4

FIGURE 1 is a side elevation of my design for a portable power shear for sheet material;

FIGURE 2 is a bottom plan view thereof;

FIGURE 3 is a view taken from the rear of FIGURE 1;

FIGURE 4 is a front view of the device as shown in FIGURE 1.

The dominant features of my design for a portable power shear reside in the portion shown in full lines on the drawings.

I claim:

The ornamental design for a portable power shear for sheet material, substantially as shown and described.
